SEWING MACHINE WITH ADJUSTABLE
CLOTH FEED-MOTION

Max Liniger, Basel, Switzerland

Application October 1, 1945, Serial No. 619,650
In Switzerland March 17, 1944

7 Claims. (Cl. 112—210)

1

My invention relates to improvements in sewing machines in general, and in particular to cloth-feed motions adjustable in operation of the machine both as to size and direction of the grip thereof; and the main object of my improvements is to afford means and facilities permitting of changing the throw of the cloth-shifter both in size and sense of operation, i. e. forward or backward, during operation of the sewing machine.

I attain this and related objects by the mechanism shown, by way of example, in one embodiment in the accompanying drawings, in which:

Fig. 1 is a longitudinal section through a portion of the free arm of a sewing machine;

Fig. 2 a similar section as in Fig. 1, but showing certain parts in another operative position;

Fig. 3 a plan view of Fig. 1 with arm uncovered;

Fig. 4 a cross-section on the line IV—IV of Fig. 1; and

Figs. 5 and 6 are cross-sectional views, leaving out certain parts, in two different adjusting positions.

The machine illustrated and described herein-after is of the portable type, comprising a free trough-like arm 1, provided with a lid 3 and which serves as support for the piece of cloth to be sewn. A cloth-feed motion is disposed in the said arm, which latter is provided with the cross-walls 2, 4 and 35 at the other end of the arm (Fig. 3). The said motion is controlled by the shaft 5 which drives the shuttle (not shown) and which is journaled on its outer end in the cross-wall 2. The said shaft is driven by a motor and always turns in the same sense. The vertically reciprocating needle performs a stitch for each complete revolution of the shaft 5.

A stationary shaft 6 is supported on the cross-walls 2 and 4, and a saddle 7 is mounted thereon which is provided with a pin 8 extending parallel to the said shafts 5 and 6. A control lever 9 is pivoted on the pin 8, and provided with a horizontal slot at the elevation of the drive shaft 5. An eccentric 15, mounted displaceable on the said shaft 5 by means of a groove and tongue, engages the said slot 10. The eccentric 15 is operatively connected with a control rod 41 through the intermediary of a forked guide 15a. The said rod 41 is longitudinally displaceable in the cross-walls 2, 4 and 35, and is provided with a lateral operating handle 42, by which the eccentric 15 may be displaced on the shaft 5 in the desired direction.

By displacing the eccentric 15 to the right, i. e.

2

from the position of Fig. 1 into that shown in Fig. 2, it is disengaged from the slot 10 so that the said control lever 9 is depressed into the position shown in the latter figure. The eccentric 15 is beveled on the side facing the control lever 9, so that by displacing the former in the other direction the lever 9 is engaged with its slot 10 on the eccentric and again occupies the position shown in Fig. 1.

10 The top end of the control lever 9 is flanged to form a head 11, on which a cloth feeder 12 is secured. By depressing the lever 9, in the manner described above, the feeder 12 is lowered below the working table so that the cloth, if such 15 is desired, may be displaced thereon unhampered. In Fig. 3 the cloth feeder 12 has been omitted for the sake of clearness.

The control lever 9 further is provided with a laterally protruding eye 13, in which a pin 14 is mounted. On the eccentric 16, which also is mounted on the shaft 5 but is turned through a right angle relative to the eccentric 15, a connecting rod 17 is pivoted, through which a pin 19 is passed. On one side of the connecting rod 17, the pin 19 carries a strap 18 which in its turn is pivoted on the pin 14. On the other side of the connecting rod the pin 19 carries a slipper 20 which is engaged in a slot 21. The latter is cut from a rotatable sliding block 22 which on 30 one part of its circumference is provided with teeth 23. The sliding block 22 is riding on the one end of a pivot 29 bearing in the cross-wall 4, and to the other end of which a set collar 30 is secured by means of a taper pin 31.

35 The helical spring 32, disposed between the set collar 30 and the cross-wall 4 on the pivot 29, constantly draws the sliding block 22 up against the cross-wall 4, thus subjecting the brake discs 33, which are disposed on the pivot 29 on the 40 other side of the said wall, to a corresponding pressure. The toothed segment 25 of a regulating block 24 keyed to an auxiliary shaft 27 engages the teeth 23. The said auxiliary shaft 27, which is pivoted in the cross-walls 4 and 35, carries a regulating lever 26 by means of which the shaft 27 may be turned for the amount desired. In the Figs. 4-6, the positions I and III indicate the terminal positions of the lever 26, while II is an intermediate position.

45 The cloth-feed motion described above operates as follows: The control lever 9 is vertically reciprocated through the intermediary of the eccentric 15 and the horizontal slot 10. The lateral movement of the lever 9 is controlled by the pin 50 14 passed through the eye 13 of the lever. The

pin 14 is connected with the pin 19 by means of the strap 18. As long as the pin 19, which is driven by the connecting rod 17, moves in the vertical median plane, the lever 9 also is held fast in this plane by means of the strap 18, and is vertically reciprocated in its turn. This is the case, when the rotatable slot 21, as shown in Fig. 3, stands vertical, since the slider 20 then is also vertically reciprocated, as well as the pin 19. When, however, the rotatable slot 21 is rocked out of its vertical position, i. e. approximately into the position of Fig. 5, the pin 19 travels from its bottom position, which is to the left of the median plane, into its top position which is to the right of the latter. The arising component of movement in a horizontal direction is transmitted, by way of the strap 18, onto the pin 14 and thus onto the control lever 9. Since the eccentrics 15 and 16 stand at right angles to each other, it is easily seen that the head portion 12 of the control lever 9 in this case describes a slightly distorted ellipse, the vertical axis of which is represented by the vertical movement of the eccentric 15, and the horizontal axis by the horizontal component of the movement of the pin 19. The ellipse is slightly distorted, since the straps 7 and 18 do not afford perfect straight guides, but possess definite radii.

The feed is regulated, and the direction of feed is reversed by turning the slide block 22, accomplished by means of the toothed regulating block 24 and the regulating lever 26 by way of the regulating shaft 27. When the shaft 26 is laid horizontal, the rotatable slot 21 stands vertical, and the control lever 9 is not moved laterally. When the lever 26, on the other hand, is in the position I or III or intermediate of I-II and II-III, the rotatable slot 21 is more or less inclined, the inclination either being from the left to the right or vice-versa. In correspondence to the angle of inclination the size of feed is established, and the feed direction of the cloth-shifter according to the sense of inclination. The size of feed thus may be changed as desired, and the sense of feed may be changed, and this during operation of the machine, since for releasing this change, only the non-following slide block 22 has to be turned.

Owing to the action of the spring 32 and the brake discs 33, the slide block 22 remains in its appointed position. To turn it, the frictional resistance of the brake discs 33 must be overcome by means of the regulating lever 26.

What I claim and desire to secure by Letters Patent is:

5 1. In a sewing machine of the character described a cloth-feed motion adapted to be changed during operation of the machine both as to extent and direction of throw, comprising an eccentric displaceably keyed to the shuttle-operating main shaft of the machine, a cloth-shifter control lever adapted to be operatively engaged with or disengaged from the said eccentric for the purpose of receiving an oscillatory vertical movement, a second eccentric keyed to the said shaft at an angular position relative to said first named eccentric, a connecting rod upon said second eccentric having a pin thereon, a transmission gear mounted on said pin for engaging said control lever for imparting oscillatory horizontal movement thereto, guide means for said pin permitting reciprocation thereof in a plane inclined to the horizontal plane, and adjusting means cooperating with said guide means for changing the plane of reciprocation of said pin for controlling the throw of the cloth-shifter both as to extent and direction.

20 2. A cloth-feed motion according to claim 1, in which the said guide means comprise a slotted slide block turned through the intermediary of the said adjusting means.

25 3. A cloth-feed motion according to claim 1, in which the said guide means comprise a slotted slide block having a toothed segment and said adjusting means includes a member having a toothed segment cooperating with said first named segment.

30 4. A cloth-feed motion according to claim 1, in which the said guide means comprise a slotted slide block keyed to a pivot, and a brake device adapted to engage the said block for the purpose of securing same against unintentional rotation.

35 5. A cloth-feed motion according to claim 1, in which the said guide means comprise a slotted slide block keyed to a pivot, and spring-loaded brake discs mounted on the said pivot to prevent unintentional rotation.

40 6. A cloth-feed motion according to claim 1, in which said transmission gear comprises a strap mounted on said pin cooperating with said control lever.

45 7. A cloth-feed motion according to claim 1, in which a manually operated lever cooperates with said first mentioned eccentric for displacing it axially into and out of engagement with said cloth-shifter to render it operative or inoperative.

MAX LINIGER.
